United States Patent

Des. 237,589
Patented Nov. 11, 1975

237,589

BOTTLE CARRIER

Rodney K. Calvert, Dunwoody, Ga., assignor to
The Mead Corporation, Dayton, Ohio

Filed July 3, 1974, Ser. No. 485,727

Term of patent 14 years

Int. Cl. D9—03

U.S. Cl. D9—178

FIG. 1

FIG. 2

FIG. 3

FIG. 4

FIG. 1 is a plan view of a bottle carrier showing my new design;

FIG. 2 is a bottom plan view;

FIG. 3 is a side elevational view, the opposite side being the same in appearance as the side shown; and

FIG. 4 is an end elevational view, the opposite end being the same in appearance as the end shown.

I claim:

The ornamental design for a bottle carrier, as shown and described.
